DESIGN FOR A CROCHET NEEDLE

Helen H. Gray, San Dimas, Calif.

Application August 28, 1943, Serial No. 111,007

Term of patent 14 years

To all whom it may concern:

Be it known that I, Helen H. Gray, a citizen of the United States, residing in San Dimas, in the county of Los Angeles and State of California, have invented a new, original, and ornamental Design for a Crochet Needle, of which the following is a specification, reference being had to the accompanying drawing, forming part thereof.

Fig. 1 is a side elevation of a crochet needle, showing my new design.

Fig. 2 is an edge view of same, looking in the direction of the arrows 2—2 of Fig. 1.

I claim:

The ornamental design for a crochet needle, substantially as shown.

HELEN H. GRAY.
